UNITED STATES PATENT OFFICE.

JOHN LINZ, OF PITTSBURGH, PENNSYLVANIA.

VENTILATOR.

Application filed August 5, 1927. Serial No. 210,941.

This invention relates to ventilators and is an improvement upon the ventilator disclosed in my copending application filed April 12, 1927 and bearing Serial No. 183,123.

5 An object of the present invention is to improve the construction of the ventilator disclosed in the above referred to application, by reducing the amount of material and time required in the manufacture of the ventilator, 10 and by simplifying the construction and operation of the shutter adjusting mechanism.

Another object of the invention is the provision of a storm cover which may be detachably secured to the ventilator, so as to prevent 15 the passage of rain or snow.

With the above and other objects in view, the invention further includes the following novel features and details of construction, to be hereinafter more fully described, illustrated in the accompanying drawings and 20 pointed out in the appended claims.

In the drawings:—

Figure 1 is a fragmentary sectional view taken through the upper portion of a window 25 with the ventilator in place.

Figure 2 is an elevation of the same.

Figure 3 is a section on the line 3—3 of 30 Figure 2 with the storm cover in place.

Figure 4 is a similar view on the line 4—4 of Figure 2.

Figure 5 is a section on the line 5—5 of Figure 3.

Figure 6 is a section on the line 6—6 of Figure 3.

Figure 7 is a fragmentary elevation of the 35 storm cover.

Figure 8 is a detail perspective view of one of the panels of the ventilator.

Figure 9 is a fragmentary sectional view 40 taken substantially on the line 9—9 of Figure 4.

Figure 10 is a detail perspective view of the shutter bar.

Figure 11 is a fragmentary elevation partly 45 in section showing the rod for adjusting the shutters.

Referring to the drawings in detail wherein like characters of reference denote corresponding parts, the reference character 11 50 indicates a ventilator frame or casing which may be arranged within a window frame or may form a part of the window sash. The frame includes top and bottom walls 12 and 13 respectively which are connected by end walls 14. A rectangular frame is thus provided. Extending from the edges of the

frame is a preferably inclined flange 15 whose outer edge 16 is straight and this edge is adapted to be received within the usual grooves 16 of the stiles and rails of a window 60 sash, which grooves ordinarily receive the edges of a window pane. In positioning the ventilator, the sash is provided with an auxiliary rail 17 having one edge arranged to receive the edge 16 of the flange 15, and 65 its opposite edge arranged to receive a window pane 18. The frame of the ventilator thus forms a part of the window sash.

Spaced within the frame are panels 19. These panels like the frame are preferably 70 formed of metal and have their edges provided with inturned flanges 20, so that these flanges are positioned upon opposite sides of passages 21 provided between the edges of the panels. The ends of the panels have 75 extending therefrom lugs 22 and these lugs are received within openings 23 provided in the top and bottom walls 12 and 13 of the frame.

Pivottally mounted as at 23 in the top and bottom walls of the frame are shutters 24. 80 These shutters are arcuate shape in cross section and the flanges 20 of the panels 19 are arranged to conform substantially to the shape of these shutters. The shutters 24 may be moved pivottally so as to close the passages 85 21, or they may be moved to regulate the size of these passages and to control the direction of travel of the air entering the passages.

The top wall 12 of the frame is provided with arcuate slots 25 which are concentric 90 with the pivots 23. These slots are adapted for the passage of studs 26 which extend from a bar 27 movable along the top wall 12. The lugs extend through the slots 25 and engage openings 25' provided in the shutters 24 so 95 that movement of the bar 27 as previously mentioned will simultaneously move the shutters upon their pivots.

For the purpose of moving the bar 27 there is provided a rod 28. This rod is mounted in 100 bearings provided in the frame 11 and has rigid with its upper end a crank arm 29. One end of this crank arm is pivottally connected to a link 30 and the latter has pivotal connection as shown at 31 with the bar 27. 105 By partially rotating the rod 28, the bar 27 will be moved longitudinally either to the right or left from the position shown by full lines in Figure 4 to the positions shown by dotted lines in said figure. In either position, the shutters will be moved to one side 110 of the passages 21 so as to entirely open these

passages. Any intermediate positions will of course only partially open the passages. In Figure 11 there is shown an operating rod 28^a, having a socket 28^b at one end to receive the lower end of the rod 28, and a handle 28^c at its opposite end, so that the rod 28 may be rotated to adjust the shutters 24. The top wall 12 of the frame has cut therefrom a strip 32 and this strip is bent over the bar 27 as shown in Figures 4 and 9 of the drawings so as to form a guide for this bar. One or more of these guides may be provided as desired.

The ventilator may include a removable storm cover 33. This cover is adapted to fit over the frame as shown in Figures 3 and 5 of the drawings and is provided with spaced openings 34 which are covered by hoods or visors 35. The cover has secured thereto spaced bars 36 and these bars are offset and provided with key hole slots 37. The slots 37 are adapted to receive headed studs 38 which extend from the panels 19 so as to removably hold the storm cover in place.

The invention is susceptible of various changes in its form, proportions and minor details of construction and the right is herein reserved to make such changes as properly fall within the scope of the appended claims.

Having described the invention what is claimed is:—

1. The combination with a ventilator including a casing open at its front and rear and having spaced panels providing passages through the ventilator with means to regulate the passages, of a cover adapted to fit the front of the casing, said cover having spaced parallel openings therein, a hood extending over each of the openings, and means to removably secure the cover to the ventilator.

2. The combination with a ventilator in-

cluding a casing open at its front and rear and having spaced panels providing passages through the ventilator with means to regulate the passages, of a cover adapted to fit the front of the casing, said cover having openings therein extending at right angles to the ventilator passages, hoods extending over the openings in the cover and means to removably secure the cover to the ventilator.

3. A ventilator comprising a casing open at its front and rear, spaced panels arranged within the casing providing passages through said casing, arcuate shutters mounted for pivotal movement between the horizontal walls of the casing to regulate the passages, and one horizontal wall of the casing having spaced arcuate-shaped slots, a bar extending along the slotted wall of the casing, a guide arm struck from the frame and extended over the bar, means carried by the bar and projecting through the slots to engage the shutters and actuate the latter when the bar is moved longitudinally and means to move the bar.

4. A ventilator comprising a casing open at its front and rear and having spaced arcuate openings in its top wall, spaced panels within the casing providing passages through said casing, arcuate shutters mounted for pivotal movement within the casing to regulate the passages, each of said shutters having an opening in one end, a longitudinally movable bar, spaced studs extending from said bar and movable within the arcuate openings and engageable within the openings of the shutters to simultaneously operate the latter when the bar is moved, and means to move the bar.

In testimony whereof I affix my signature.
JOHN LINZ.
